LOUDSPEAKER DIAPHRAGM AND METHOD
OF FABRICATING THE SAMEEdward J. Wiest, Oak Lane, Pa., assignor to Radio
Corporation of America, New York, N. Y., a
corporation of Delaware

Application July 31, 1940, Serial No. 348,862

5 Claims. (Cl. 179—115.5)

This invention relates to acoustic diaphragms for loudspeakers, and more particularly to the method of fabricating the same.

It has long been recognized that, in loudspeakers of the electrodynamic type, it is desirable to place a dust cap over the hollow voice coil form to prevent dust from entering into the air-gap between the coil form and the magnet structure. The customary practice is to form the dust cap separately from the diaphragm and to apply the cap to the voice coil form after the form has been secured to the diaphragm.

It has also been customary to form diaphragms out of paper flock by a felting process in which the fibres are suspended in water and are sucked onto a preformed screen to give the diaphragm the desired shape. One such form or screen is so shaped that a hollow, central projection is provided on the diaphragm through which the voice coil form may be inserted for attachment to the diaphragm. The end of this projection is closed off during the felting process, and this end must, obviously, be cut off in order to permit insertion of the voice coil form. Heretofore, these ends have been discarded and separate dust caps have been fabricated to place over one end of the voice coil form, thus necessitating additional expense and additional manufacturing steps and material, a substantial part of the felted diaphragm going to waste.

The primary object of my invention is to provide an improved method of fabricating diaphragms of the type set forth which are not subject to the aforementioned defect.

More particularly, it is an object of my invention to provide a novel method of manufacturing diaphragms for loudspeakers of the type under consideration which will require a minimum number of parts and a minimum number of operations during fabrication.

Another object of my invention is to provide an improved method of fabricating loudspeaker diaphragms which is very economical, highly efficient, and which results in an improved diaphragm structure.

In accordance with my invention, instead of discarding the closed end of the cylindrical projection of which the diaphragm is originally formed, I employ this end portion as a cap member and place it over one end of the voice coil form after the latter has been secured to the diaphragm. Obviously, since the cap is cut off from the cylindrical projection or flange through which the voice coil form is inserted and to which it is cemented or otherwise suitably secured, it has

the same diameter as this flange and therefore fits snugly over the end of the voice coil form. In this way, the manufacture of separate dust caps and waste of diaphragm material are eliminated, and an efficient diaphragm is provided.

The novel features that I consider characteristic of my invention are set forth with particularity in the appended claims. The invention itself, however, both as to the method in which it may be practiced and the resulting diaphragm, together with additional objects and advantages thereof, will best be understood from the following description of one embodiment thereof, when read in connection with the accompanying drawings, in which

Figure 1 is a view, partly in section, of a felted diaphragm after it has been removed from the felting apparatus and dried.

Figure 2 is a similar view with the cap member severed from and in separated relation to the attaching flange on the diaphragm.

Figure 3 is an enlarged sectional view showing the voice coil form in place on the diaphragm, and

Figure 4 is an enlarged sectional view showing the cap member applied to the voice coil form.

Referring more particularly to the drawing, wherein similar reference characters designate corresponding parts throughout, I have shown a frusto-conical diaphragm 1, which may be felted in the manner noted above or formed in any other suitable manner, and which is provided with an outwardly extending, central, hollow, cylindrical projection 3 having a closed end 5. As the first step in practicing my invention after the diaphragm 1 has been formed, the projection 3 may be cut or severed along a plane intermediate its ends and normal to its axis. Such a plane is designated by the dash line A—A in Fig. 1. When this step has been completed, the resulting diaphragm 1 is provided with an outwardly extending, central, open ended flange 3a and a cap member having the closed end 5 and a cylindrical surface 3b which is a continuation of and therefore has the same diameter as the flange 3a.

A tubular, cylindrical voice coil form 7 on which may be wound one or more turns of wire to form a suitable voice coil 9 is next inserted through the opening of the diaphragm provided by the flange 3a. The external diameter of the voice coil form 7 is preferably the same as the internal diameter of the flange 3a, and it is secured to the flange 3a in any suitable way, as by cement or varnish. Preferably, the voice coil form 7 extends through the flange 3a to a point where the end 7a there-

of, adjacent which the coil 8 is wound, lies on one side of the diaphragm and its opposite end 7b is on the opposite side of the diaphragm. After the voice coil form 7 has been secured in place, the cap member may be fitted over the end 7b thereof and secured thereon by cement or the like. The flange 8b of the cap member being of the same diameter as the flange 8a left on the diaphragm 1, it is obvious that the cap member will fit snugly over the coil form 7, the end 8 of the cap member completely closing the end 7b of the voice coil form and therefore acting as a dust cap therefor.

Although I have shown and described but one embodiment of my invention, it will be obvious to those skilled in the art that a number of variations may be made therein. For example, instead of making the projection 3 extend outwardly of the frusto-conical diaphragm 1, it may be made to extend inwardly, and the same process as above described may be carried out with respect to it. Also, instead of winding the coil 8 on the end 7a of the voice coil form, it may be wound on the end 7b thereof and the dust cap placed over the end 7a of the coil form. Other similar changes will, no doubt, readily suggest themselves to those skilled in the art. I therefore desire that my invention shall not be limited except insofar as is made necessary by the prior art and by the spirit of the appended claims.

I claim as my invention:

1. The method of fabricating a frusto-conical acoustical diaphragm which comprises forming the diaphragm with a closed, hollow, outwardly extending projection on its apex end, removing the closed end of said projection to provide the diaphragm with an opening, inserting a voice coil form in said opening and securing said form to said diaphragm, and finally applying said removed end to one end of said form and securing said end thereto.

2. The method of fabricating a frusto-conical acoustical diaphragm which comprises forming the diaphragm with a closed, hollow, outwardly extending projection on its apex end, severing said projection transversely thereof to form an opening in the diaphragm and to provide a cap member, inserting a tubular voice coil form in said opening and securing said form to said dia-

phragm, and finally applying said cap member over one end of said form and securing said cap member thereto.

3. The method of fabricating a frusto-conical acoustical diaphragm which comprises forming the diaphragm with a hollow, outwardly extending projection on its apex end the outer end of which is closed, severing said projection along a plane substantially normal to the axis of said projection to provide an opening through said diaphragm and to provide a cap member constituted by said outer, severed end, inserting a tubular voice coil form through said opening and securing said form to said diaphragm, and finally fitting said cap member over one end of said form and securing said cap member thereto.

4. The method of fabricating a frusto-conical acoustical diaphragm which comprises forming the diaphragm with a hollow, outwardly extending projection on its apex end which is closed at its outer end and which extends substantially coaxially from the diaphragm, severing said projection along a plane substantially normal to the axis of said projection to provide a substantially central opening through said diaphragm and to provide a cap member constituted by said outer, severed end, inserting a tubular voice coil form through said opening and securing said form to said diaphragm, and finally fitting said cap member over one end of said form and securing said cap member thereto.

5. The method of fabricating a frusto-conical acoustical diaphragm which comprises forming the diaphragm with a substantially central, hollow, outwardly extending cylindrical projection on its apex end which is closed at its outer end, severing said projection intermediate its ends along a plane substantially normal to its axis whereby to provide an annular flange on said diaphragm defining an opening therethrough and a severed cap member also having an annular flange which is a continuation of said first named flange, inserting a cylindrical voice coil form through said opening and securing said form to said first named flange, and finally fitting said cap member over one end of said form and securing said second named flange thereto whereby to fix said cap member to said form.

EDWARD J. WIEST.
